UNITED STATES PATENT OFFICE

WEST DODD, OF DES MOINES, IOWA

SYSTEM FOR PROTECTING PETROLEUM TANKS AND TANK FARMS AGAINST LIGHTNING AND ELECTRICAL SPARKS

Application filed May 31, 1927. Serial No. 195,398.

My present invention has for its general purpose to provide a system for protecting petroleum tanks and tank farms against lightning and electrical sparks.

- 5 It is more particularly my purpose in this connection to provide such a system comprising apparatus including elements so constructed and arranged that "sparking" and "direct hits" at the tanks will be prevented.
- 10 A further purpose is to provide such an apparatus whereby electrical charges from the earth entering the conductive parts of the tanks will be expelled from the entire tank structure and conducted away from the
- 15 tanks to points of discharge located a safe distance from and preferably above the roofs of the tanks.

This application is a continuation in part of my application theretofore filed on May 20 15, 1926, Serial No. 109,310, and issued as Patent No. 1,691,340, dated November 13, 1928.

With these and other objects in view, my invention consists in the construction, arrangement and combination of the various parts of my system, whereby the objects contemplated are attained, as hereinafter more fully set forth, pointed out in my claims, and illustrated in the accompanying drawings, in

30 which:

Figure 1 shows a diagrammatic plan view of a tank farm including a series of tanks of the well-known sectional built-up metallic construction having installed in connection therewith apparatus embodying my system.

Figure 2 is an elevation partly in section illustrating part of the apparatus taken on the line 2—2 of Figure 1; and

40 Figure 3 is a top or plan view of one of the tanks equipped with my apparatus.

It is a fact of general knowledge that in oil fields and other places where petroleum is stored in tanks, immense losses occur as 45 result of fire caused by electrical sparks and lightning.

Petroleum tank fires from lightning causes 50 may occur in two different ways, viz: by electro-static sparks among inflammable gases at the instant of a lightning discharge at

some distance, or by a "direct lightning hit" at the tank.

Sheets of metal are usually nailed on a wood roof of a tank. These metallic sheets are seldom in metallic union and sparks occur 55 in the electrical resistance gaps between these metallic sheets, if a lightning discharge is near, or through its influence if near a connecting pipe line, and these sparks in inflammable gases will start a fire, just as in the 60 automobile engine.

The other and surer way is by a "direct lightning hit" at the tank rim where the inflammable gases most generously escape.

I may here state:—Lightning or electrostatic sparks or so-called lightning strokes result from previous electric conditions induced or attracted from earth into the metallic or conductive parts of the tank by an approaching overhead oppositely electrically 65 charged cloud.

When a cloud, carrying an electrical charge, is passing, it induces a complementary charge, of opposite sign, on a substantially corresponding area of the earth's surface, and the metallic pipe lines, associated with the tanks and extending out into the earth electrical field or charge, readily focus 75 the earth charge on the tanks.

When a cloud discharges by a lightning 80 flash, the tanks instantly discharge to earth at the same instant and that endangers the tank, either by electro-static sparks on the roof in any gaps between the metallic parts, or by a "direct lightning hit."

When a tank fire occurs by a "direct lightning hit," the flash is uniformly at the tank rim or winch near the tank rim. This is because of the rather flat tank roof, by which the law of repellence of similar sign electricity can readily focalize the induced electrical charge seeking its path of least resistance through the wall of the tank more densely at the tank rim and among the inflammable escaping gases, than anywhere else 95 on the tank.

In providing the apparatus comprising my system, I have in view the following additional principles:

First. I desire to so far as possible pre- 100

vent the accumulation of electrical charges on the tank. I do this in the belief that where there is less electrical charge, there is less likelihood of a spark or "direct hit."

5 Second, I desire to provide means for preventing either a spark or "direct hit" on or at the tank.

These desirable results are attained in the following manner:

10 In the drawings herewith, I have used the reference numerals 10 and 10^a to indicate diagrammatically the roof and side wall of petroleum tanks of the well-known sectional metallic construction, which may be arranged 15 in a farm as shown in Figure 1.

14 is a protecting wall surrounding the tank.

19 and 20 designate the electrically conductive joints between the sections of the tank 20 roof.

Ordinarily, there are pipe lines 12 leading to and from the farm and branches 12^d connecting the main pipe lines with the respective tanks.

25 In order, so far as may be possible to avoid a strong electrical charge in the bodies of the tanks from the earth electrical charge through the pipe lines, I erect tall metallic towers 16 with terminal points 18 on the pipe lines at 30 safe distances outside of the tank farm. These towers and their points serve two important functions, one of which is to offer a preferred path for the lightning discharge, rather than among the tanks, and the other 35 to silently discharge electricity as much as may be in order to minimize the lightning stroke and even tend to prevent it.

As stated "the law of self-repulsion of similar sign electricity focuses any charge of electricity, induced on a tank more densely at the 40 tank rim than anywhere else on the tank roof. For that reason, a lightning hit or discharge is always at the rim of any ordinary tank."

In order to provide against such lightning 45 discharge at the tank rim and also lessen the sparking possibilities on the tank roof, I arrange around and apart from each tank the posts 22, the terminal points of which are preferably some higher than the tanks, but 50 not as high as the tower points 18. The posts 22 are to be firmly set in the ground, preferably in concrete, and electrically connected by conductors 24 with the tank at their bases adjacent to the bottom of the tank above the 55 surface of the ground as shown in the drawing for clearness, or, if desired, below the surface of the ground to thereby cover and conceal the connections from exposure.

It is of much importance that these electric 60 connections be made at the bottom of the tank and not at the top, to be removed as far as may be from the inflammable escaping gases at the tank roof or the edges thereof. Excessive heat is frequently created at joint 65 connections, even to melting, and any joint con-

nections made at the top of the tank would be subject to serious strains, due to the coefficient of tank expansion and contraction, creating a push and pull strain tending to loosen the joints, which would be further augmented by wind pressure on the posts 22.

The series of posts 22 around each tank are preferably electrically connected together near their upper ends by metallic conductors such as the cable 26.

75 The effect of this arrangement of posts with their terminal points and tank connections permits the law of "self-repulsions of similar sign electricity" to focus or localize the electric discharge expelled from the tank 80 at the points and connecting cable spaced from and surrounding the tanks and not at the tank rim as indicated by the line 28, Fig. 2. It is practically the same as to set the rim of the tank out and away from the places 85 where gases escape, so that lightning can only occur at the surrounding points and cable, and never at the tank.

To recapitulate and epitomize:

An electrically charged cloud induces or 90 attracts an electrical charge of opposite sign on the earth's surface and about a tank.

The law of "self-repulsion of similar sign electricity" focusses and discharges the earth's charge from the tank at the tank rim from 95 which cause lightning occurs at the tank rim.

This law of "self repulsion of similar sign electricity" is the key to tank protection when intelligent means for its operation is installed.

100 The means herein described are so related to the tank that this law is operative effectively and focuses and discharges the electricity expelled from the tanks to distantly localized points away from the tanks on the 105 surrounding equipment as described, and experimental research shows the law is never failing, and a discharge of electricity at any place on the tank impossible.

110 It will be understood that the parts of the system may be constructed and arranged in different ways without departing from the real spirit and purpose of my invention, and it is my intention to cover by my claims any modified forms of structure or use of mechanical equivalents, which may be reasonably included within their scope.

I claim as my invention:

1. In a system for protecting tanks against lightning, the combination with a tank having a roof and side walls of electrically connected conductive material, of a plurality of metallic points spaced from the side wall of the tank and extending to a height greater than that of the tank, and means for electrically connecting the said points to the lower edge of the tank only, adjacent to the ground or other support.

120 2. In a system for protecting tanks against lightning, the combination with a tank hav-

125 65

ing a roof and a wall of conductive material electrically connected, of a plurality of metallic points spaced from the tank there-around, and extending to a greater height than that of the tank, means for electrically connecting each point to the bottom only of the tank at the ground or other support for the tank, and means for connecting the upper parts of the points together in series.

5 3. In a system for protecting tanks against lightning, the combination with a tank having a roof and side walls of electrically connected conductive material, of a plurality of metallic posts having terminal points spaced 10 from the side wall of the tank, and means for electrically connecting the said posts to the lower edge of the tank only adjacent to the ground or other support for the tank.
